The schedule referred to in these Letters Patent and making part of the same

Be it known that I, Henry Miskler of Mogadore,

same, reference being had to the accompanying drawings forming a part
of this specification, and in which:-

In the drawings, A, represents the horizontal
bottom, and B, the inclined sides of the inner surface of the plate; C,
represents the rim with a flat narrow top, D, a perpendicular outer edge
E, and a narrow horizontal bottom projection F, while G, represents the flat

The outer conical part of the plate from 1 to 2,

indicating the dividing lines and the letters a, a, the concave surfaces.

In plates of the above design the form or design
of the plate is such as to render it both attractive and pleasing to the eye.

What I claim and desire to secure by Letters
